MILLING MACHINE

Harvey M. Braucher, Baltimore, Md.

Application August 12, 1944, Serial No. 549,243

5 Claims. (Cl. 90—14)

(Granted under the act of March 3, 1883, as amended April 30, 1928; 370 O. G. 757)

1

The invention described herein may be manufactured and used by or for the Government for governmental purposes without the payment to me of any royalty thereon.

My invention relates to milling or work processing machines and more particularly to machines for milling or processing the ends of cartridge cups.

At the present time improperly drawn cartridge cups are produced and many of such cups accumulate at the arsenals. A primary object of my invention contemplates the reconditioning and correcting of these improperly shaped cups within the limits of Government specifications whereby the cups do not have to be sent back to the copper companies to be remelted and converted a second time into bars to be again formed into cartridge cups.

A further object is to provide a semi-automatic machine with novel features to mill the open ends of cartridge cups.

A still further object is to provide means whereby cups of varying height may be reconditioned.

Another object is to provide a novel cutter and dial feed arrangement.

Other advantages and objects will be apparent from the following description in which like numerals designate like parts in all views.

Figure 1 is a side elevational view of the milling machine with a portion of the driving belt broken away.

Figure 2 is a top plan view of the power transmitter and dial feed broken away to show the sliding clamp members and pusher member.

Figure 3 is a view taken on the line 3—3 of Figure 1.

Figure 4 is a fragmentary view taken on the line 4—4 of Fig. 3.

Figure 5 is a fragmentary view of the cam mounted on a bracket for providing reciprocating movement to the cutter.

Figure 6 is a fragmentary top plan view of the connecting link shown in position in Fig. 1.

Figure 7 is a perspective view of the dial operating cam, and

Figure 8 is a fragmentary perspective view of the pocketed dial member and guiding plate for the sliding clamp members.

In the drawings 8 designates the base of the machine on which a power transmitter 9 is mounted and 10 is a pedestal on which is arranged a rotatable cartridge cup dial feed 11. A

2

stationary housing 12 surrounds the dial feed and is supported by standards 13.

Associated with said dial feed is a milling tool 14 which is supported by a bracket 15 extending upwardly from the base 8 and additional brackets secured to 15 are designated at 16, 17, and 18 which are provided for supporting the working parts of the cutter.

It will be noted that the cutter 14 is provided with reciprocal and rotatable movements. Such movements are obtained through a novel connection means with the power transmitter 9. The power transmitter receives its power from a belt 19 or any suitable means and the reciprocating movement is obtained from a take-off 20 (Fig. 2) on said power transmitter. A vertical drive shaft 21 extends upwardly from said take-off where it is geared at 22 to gear 23 of a horizontal drive shaft 24, said shafts 21 and 24 being supported by bracket 25 carried by a main support 26 (Fig. 2). At the opposite end of this shaft 24 is a cam 27 arranged within a yoke 28. Stems 29 and 30 are carried by said yoke, the stem 29 being guided in the bracket 16. The lower stem 30 is secured to a coupling member which will be described at a later point.

Rotatable movement to the cutter 14 is given through a take-off 31 meshing with a gear 32 near the bottom of a vertical shaft 33 journaled in the bearing 34. This shaft rigidly supported by bracket 34 mounted on the upright 95 carries a sprocket 35 and a driving chain 36 connects said sprocket 35 to a second sprocket 37 carried on the sprocket hub 38 of the cutter 14. The inner surface of the hub 38 is fitted with keyways in which are mounted keys 39 which are keyed to the spindle member 42 for providing rotary movement to the cutter. The cutter 14 is fitted with the cutting tool 40 which is adjustably and resiliently mounted in said cutter to provide a touch milling feature.

Numerical 42 denotes a bushing in which rotates and slides the spindle 42. This spindle is connected to the stem 30 through a coupling joint 43 and 44 secured together by fastening means 45. The part 43 is secured to stem 30 in any suitable manner and may be held by a set screw 43' and part 44 is shouldered to fit a groove 46 in spindle 42. The member 44 further serves as a thrust bearing for the spindle.

The cutting tool 40 is bolted to a plunger 47 which can slide inside the spindle 42 but is limited in its travel by drive pin 48 extending 55 through the plunger stem 47' and a slotted hole

48' in the spindle 42. One end of a compression spring 49 bears against an internal shoulder 50 in the spindle 42 and the other end bears against an adjustable nut 51 threaded on the plunger stem 47'. The combination of the nut 51, spring 49 and drive pin 48 gives the cutting tool 40 the balance and pressure necessary to produce the desired cut. Also, the arrangement permits the use of various size cups. In the ordinary milling machine products identical in dimensions are produced while in the present invention dimensions may vary but the weights must be nominally the same.

A low speed shaft extension 52 is connected to the power transmitter 9 by a crank disc 53 to impart intermittent motion to the dial feed 11 through a pawl and ratchet movement. The crank pin is indicated at 54 and the rod 52 may be made adjustable to permit close adjustment in the length of the rod. A wrist pin 55 passes through the rod 52 and a forked link 56, while a pivot pin 58 (Fig. 6) connects the link to a pawl arm 57.

A spider 59 provided with a hub 59' rotates on pedestal 10 to transmit power from a ratchet wheel 60 to the dial 61 by means of fastenings 62. A bushing for the hub of said spider is shown at 63, and on the outside of said hub 59' is a key 64 whereby said spider 59 and ratchet 60 are coupled together.

Resting on a shoulder of the pedestal 10 and free to rotate on the hub 59' is the pawl arm 57. On a washer 65 at the end of the pawl arm 57 is mounted a pawl 66. The pawl is held to the arm 57 by a bolt 66' and is free to turn. On the underside of the stationary housing 12 is fastened an arm 68 and a tension spring 69 is hooked to a stud 10 carried by said arm and to a stud 67 carried by a pawl 66 whereby the pawl is held against the teeth 60' of the ratchet wheel 60.

Inside the stationary housing 12 is a dial ring 71 which is stationary and the cartridge cups ride on the top of this ring. The inside wall of the ring 71 is shaped to form an eccentric cam 71' in order to hold the sliding clamp members 74 open when the cups 13 are inserted in the pockets 75 of the dial 61 and to permit the outward movement of the pusher 78 and clamps 74 opposite the cutter when the cup is to be firmly gripped.

The sliding clamp members 74 work in guides 74' formed by guide walls 75' on the dial 61. The dial 61 is extended at 61' to form a lip wherein the pockets 75 are formed. These guides 74' are merely extensions of the cup receiving pockets 75. Also, the sliding clamps are preferably formed with a concave face 83 to conform to the configuration of the cups. The combination of the wall 71' of the ring 71, and inner wall of the plate 80 and also member 78 serves to act as a track whereby the movement of the clamps is guided to and away from the cartridge cups.

To the upper end of the pedestal is keyed at 16' (Fig. 2) a spring arm 76 into which a pusher 77 works. This pusher member is provided with a round stem and a convex head 78 and a compression spring 79 urges the pusher against the end of a sliding clamp 74 whereby to grip a cup tightly while it is being milled. The head of the pusher acts as a cam to nose the clamps outwardly as they approach the milling or cutting position. The eccentricity of the inner wall 71' of the dial ring 71 permits this outward movement. A plate 80 serves as an inner guide for the clamps, but is cut away at 80' to provide for the working of the member 77 where the head

78 takes over and serves to act as the guide. The plate (Fig. 8) overlaps a flange 90 and guide lugs 91 are carried by said plate.

To bring each cup to a stop directly under the milling cutter there must be no drift in the dial movement. To prevent such drift a stop device is mounted under the ratchet wheel. Projecting downwardly from said wheel are a series of pins or studs 81 equally spaced in a circle and in number corresponding to the pockets in the dial 61. A roller 82 is mounted on the outer end of the pawl arm 57. A bracket 83 (Fig. 1) bolted to the underside of the housing 12 provides a pivotal connection 84' for a cam member 84. A second bracket 85 is secured to the housing 12 and a tension spring 86 connects said bracket with a depending stud 87' carried by the cam 84 whereby the irregular cut-out portion 87 of the cam head 88 is held against the roller 82. The outline of the cam surface 87 produces the desired holding and releasing effects. On the forward stroke of the connecting rod the pawl turns the ratchet wheel until a pin 81 is stopped and held by the cam head 88. As the connecting rod 52 approaches the end of the return stroke roller 82 pushes the cam out of the path of the pin and continues to hold it that way for the early part of the forward stroke thus allowing the dial to advance another notch or step.

A table 89 is shown mounted on the pedestal 10 for receiving a supply of cartridge cups from which they are placed in the pockets 75 of the dial 61.

In the operation of the machine cups are fed on the table whence they are placed upright by hand in the pockets of the dial feed. The dial turns intermittently thereby carrying the cups successively under the continuously rotating milling cutter 40. With the cup at rest and gripped in its pocket in an upright position the cutter descends thru operation of the cam member 27 and trims the cup end. The amount of metal removed is small so that the weight of the cup remains within the limits set forth in its specifications.

After the milling operation the cutter rises, the dial feed advances a step and as the cup advances it is released and discharged by gravity through a hole 92 in ring 71 and housing 12 and another cup advances under the cutter for its trimming operation.

The drive shafts are all connected to one prime mover in such a manner as to give the desired speeds so that the movements of the dial and milling cutter are always in synchronism.

It is to be understood that while I have shown and described what is a preferred embodiment of my invention various changes in the shape, size, arrangement of parts may be resorted to without departing from the spirit of my invention and scope of the subjoined claims.

I claim:

1. In a machine for processing work pieces wherein a processing tool is moved intermittently into work engaging position, a work holder comprising a stationary housing, a rotatable dial ring in said housing, a rotatable dial and means for rotating it with a step-by-step movement, said dial being provided with a plurality of inwardly opening radially arranged recesses whose outer ends overlie the dial ring and together with said ring form pockets for the work pieces, said dial ring being provided adjacent a point of stoppage of said dial with a cutaway portion, a slideable work holding clamp in each recess arranged to

be moved at the point of stoppage of the dial to clamp the work piece, each clamp being provided with a shoulder in engagement with the inner periphery of said dial ring to hold said clamps open except when opposite the cutaway portion of the ring, and means for moving said clamp members to clamp the work when opposite said cutaway portion, said cutaway portion of the ring being so shaped as to actuate the clamps to cause them to release the work pieces upon movement of the dial beyond the processing station of the work pieces.

2. The invention of claim 1 characterized in that the means for moving the clamp members into work clamping position comprises a spring-backed cam.

3. The invention of claim 1 characterized in that there is a plate within the dial ring rotatable with said dial for at least partially supporting the slidable clamp members.

4. The invention of claim 1 characterized in that there is a stationary plate within the dial ring for limiting the inward movement of the clamp members except at the point at which said clamp members are actuated to clamp the work piece.

5. In a machine for processing work pieces, wherein a processing tool is moved intermittently into work engaging position, a work holder comprising a stationary housing, a shaft vertically disposed with respect to said housing, a spider 30 rotatably mounted on said shaft, a dial secured

to said spider and provided with a plurality of inwardly opening recesses, a stationary dial ring underlying the outer ends of the recesses which with said outer ends form pockets for the work piece, a slidable work clamping member in each recess, pawl and ratchet mechanism for rotating the spider and consequently the dial, with a step-by-step movement, cam means for actuating the clamp members at points of stoppage of the dial for clamping the work piece while being operated upon by the processing tool, and means carried by the dial ring for locking the clamp members in open position after they have passed beyond the processing station of the work pieces.

15 HARVEY M. BRAUCHER.
